ARTIFICIAL HAND

Frank L. Dale, New York, N. Y.

Application January 30, 1946, Serial No. 644,359

1 Claim. (Cl. 3—12)

1

This invention relates to artificial limbs, and more particularly to an artificial hand which may be used with a natural or artificial arm.

At the present time artificial hands do not resemble a human hand and in most instances depend upon a three-pronged or hooked member to perform the function required.

An object of this invention is to provide a hand which to outward appearances resembles a human hand and which will function as nearly as possible in the same manner as a human hand. It is my purpose to provide a hand with four fingers and a thumb which may be so manipulated so that the fist can be closed and held closed about an object without undue discomfort to the wearer.

A further object is to provide a hand in which the relationship between the thumb and the respective fingers is such that when the thumb and one finger engage an object the other fingers will close naturally in the same manner as the human hand. Most artificial hands that are available today are operated and depend for their operation upon the action or movement of the opposing arm or shoulder and require that the wearer maintains his upper body in a somewhat semi-rigid position in order to hold the hand in any predetermined position. It is one of the purposes of this invention, therefore, to provide means for operating my improved hand which will be totally independent of everything except the shoulder or upper arm of the wearer and the relationship of that member to the body.

While I have disclosed a hand which is attached to a human arm below the elbow, my hand can be attached to an artificial arm above the elbow as long as the shoulder and armpit are left and, in fact, can be attached to any artificial arm and operated by another portion of the body.

In the accompanying drawings—

Fig. 1 is a view partly in cross-section showing a preferred form of my hand.

Fig. 2 is a view in detail of the finger operating mechanism.

Fig. 3 is an enlarged detail in cross-section showing the operation of the fingers.

Fig. 4 is a cross-sectional view taken on the line 4—4 of Fig. 3.

Fig. 5 is a somewhat enlarged cross-sectional view of the bag designed to supply pressure to operate the hand.

Fig. 6 is a view showing a modified means for operating my hand.

Fig. 7 is a further modification.

Fig. 8 is a detailed view of part of the mech-

2

anism shown in Fig. 7 taken on the line 8—8 of Fig. 9.

Fig. 9 is a view taken on the line 9—9 of Fig. 8.

Referring more particularly to the drawings, 5 my improved hand 10 is adapted to be attached to a fitting 11 by means of a simple bayonet plug 12 or by any other suitable means. The fitting 11 will, of course, have to be made to fit the stub 14 of the arm 15. The entire hand and the fitting 10 are covered with an outer covering extending from the fingertips to the upper part of the fitting which may be made of rubber or other flexible material resembling skin. Through the fitting 11 is a channel 18 to accommodate the tube 19. 15 The tube 19 communicates with the bag 20 made of air-tight material and positioned between the straps 21 about the shoulder under the armpit of the wearer against the body 22. The bag 20 is provided with a spring 23 which bears against a 20 simple valve 24 having a seat 25 to normally open the valve to allow the bag to fill with air. The valve 24 is positioned against the inside of the arm of the wearer so that when pressure is applied against the arm the valve 24 will close and air 25 will be forced down the tube 19.

The hand, itself, is made of a rigid casting of plastic or aluminum 30 to which the fingers 31, 32, 33 and 34 and the thumb 35 are hinged. In the detailed view shown in Fig. 3 the hinge 36 30 represents the knuckle joint. The hinge 37 corresponds to the middle joint and the hinge 38 to the outer joint of each finger. The fingers may be made of hollow tubular material or of sheet metal pressed into channel shape. Extending through 35 each finger is a spring cable 40 which is fastened by means of pins 41, or otherwise, to the tip of the finger. The spring member 40 extends through a channel 42 which is located at the inner side of the finger so that when tension is placed 40 upon the cable 40 the finger will be caused to bend in the same manner as the human finger. Each of the cables in the fingers is engaged by an arm, the cables in the fingers 31 and 32 being engaged by an arm 45, the cables in the fingers 33 and 34 45 being engaged by an arm 46. The arms 45 and 46 are in turn engaged by the pivotal links 47 and 48 to the arm 49, which, in turn, are connected by the link 50 to the lever 51. The lever 51 is pivoted at one end to the link 52 fastened to the casting 30. 50

Mounted within the casting 30 is a block 55 containing a cylinder 56 and a cylinder 57. Within the cylinder 56 is a shaft 58 upon which the piston 59 slides. The piston 59 is provided with 55 a gasket 60 to insure contact. The shaft 58 is

hollow and provided at its top end with an opening 62 into the cylinder 56, which terminates in a nipple 63 to which the tube 19 may be clamped. Mounted in the cylinder 57 is a piston 65 having a gasket 66 and operating against the spring 61. A vent 68 is provided for the passage of air. A rod 69 extends through the packing 70 from the piston 65 to engage the lever 51. The thumb cable 71 is attached directly to the end 72 of the lever 51.

When the hand is extended the piston 59 will be at the upper end of the cylinder 56 while the piston 65 will be at the lower end of the cylinder 57. In Fig. 2 they are shown in the halfway position. A fluid, such as oil, is positioned below both pistons and passes through the opening 75 as the pistons change their relative positions. If the wearer desires to pick up an object such as a glass, he would reach for it in the normal way and then exert pressure with his upper arm against the bag 20, thus forcing air from the bag through the tube 19 into the cylinder 56, causing the piston 59 to force the fluid from the cylinder 56 into the cylinder 57 through the opening 75 which, in turn, forces the piston 65 upwardly, exerting pressure on the lever 51 and through the yoke arrangement to the respective fingers and thumb cables causing the hand to close about the glass. If an object of some weight is to be picked up so that the grip must be secure, the wearer may pump additional air into the cylinder 56 by releasing the bag and allowing it to fill. The opening 75 is of such a nature that the oil will not flow back as quickly as the air bag can be refilled and pressure again exerted on it. It will be appreciated, therefore, that considerable pressure can be exerted and a firm grip established on any object desired. If an object such as a pencil is to be picked up by the thumb and forefinger the action of the yoke arrangement on the linkage between the arms 45, 46, 49 and the leather 50 is such that when the thumb and forefinger have contacted the pencil the pressure is forced to the other fingers and the remaining three fingers will close naturally. By the same token, if the thumb and first two fingers engage an object, the opposition encountered will cause the yoke arrangement to transfer further movement to the last two fingers so that they will close in a natural position. Where an object which is irregular in shape is grasped by the entire hand the tubular yoke arrangement will cause the pressure to be transferred equally to all fingers to allow for the irregularity.

As heretofore stated, the entire mechanism from the knuckle to above the wrist is mounted in a casting and the fingers hinged to said casting. The entire device is then encased in a removable padded glove of rubber or skinlike material which extends above the fitting block 11. Artificial nails can be mounted in the glove member and the glove member can readily be removed for cleaning or replacing.

It will also be appreciated that while I have shown round cable members in each of the fingers, flat spring members may be provided which will tend to open the hand immediately upon relaxation of the tension in the pressure of the cylinders. This may or may not be supplemented by the action of the spring 67, which, when the valve 24 is released, will force the fluid into the cylinder 56 to extend the hand.

In the modification shown in Figs. 6 and 7 the construction of the hand and fingers is substantially the same, however, instead of the bag 20 a shield member 80 having a hinge 81 is attached

to the armpit by means of the straps 82. Hinged to the shield at 83 is a similar hinged member 86. Each of the members 84 and 86 are hinged together at 87 and attached to the cable 88. The cable 88 runs directly to the lever 51 so that when the arm is moved inwardly the hinge 87 is moved upwardly toward the armpit to exert pressure on the cable 88 and, in turn, on the lever 51, which will close the hand in the manner heretofore described. In the form shown in Fig. 7 the leather 51 is engaged by a cable 90 mounted on the drum 91. The drum 91 is mounted on the shaft 92 which carries a bevelled gear 93 meshing with the bevelled gear 94 on the shaft 95 controlled by the flexible cable 96. This cable 96 extends into the box 97 and engages the shaft 98 upon which is mounted the gear 99, and which is supported by the bracket 100. The gear 99 engages the gears 101 and 102 mounted respectively on the shafts 103 and 104 which carry the pinions 105 and 106 engaged by the racks 107 and 108. The racks 107 and 108 are mounted on a contact member 109, normally spaced from the box 97 by means of the springs 110 on the pins 111 and 112 and on the pin 114. When the contact member 109 is pressed against the body the rack will cause the pinions to turn on the shafts 103 and 104. This rotation will be transmitted through the gear 99 from the shaft 98 to the cable 96 and, in turn, through the gearing to the drum 91, shortening the cable 90 and exerting a pulling motion on the leather 51. The springs 115 can be added to supplement the linkage and to give greater flexibility.

It is understood that while I have shown this means for actuating my hand the function of the hand is substantially the same and the relative movement of the fingers depending upon their contact with an object results in each case from the double yoke arrangement whereby when certain fingers meet opposition the other fingers being free to move will close naturally and all four fingers and the thumb can be used to simulate the natural hand much more closely than has heretofore been possible.

In addition to the equalizing members, or yoke arrangement, it is possible with my hand to use a covering which will more nearly resemble the human hand in appearance as well as in color and consistency.

I claim:

In an artificial hand having a thumb and four fingers, members for closing each finger, each of said members engaging one end of one of a pair of arms, linkage between said pair of arms and a third arm and additional linkage between said third arm and a lever, means for operating said lever to transmit through said linkage and said arms tension on said retractable members to close said hand, said means comprising a pair of cylinders mounted in said hand, pistons in said cylinders, one of said pistons having a shaft engaging said lever and means for forcing air into the other of said cylinders to force fluid from said cylinder into the other cylinder to operate the piston in said cylinder comprising a bag worn between the arm and body of the wearer, a valve in said bag controlled by the wearer and a tube communicating from said bag to said cylinder whereby the exertion of pressure against said bag will force air out of said bag through said tube into said cylinder to operate said pistons.
